(57) **CLAIM**

The ornamental design for an inflatable frame for inflatable bed, as shown and described.

DESCRIPTION

FIG. 1 is a first perspective view of an inflatable frame for inflatable bed;

FIG. 2 is a second perspective view of an inflatable frame for inflatable bed;

FIG. 3 is a side elevational view of an inflatable frame for inflatable bed, the other side being identical; and,

FIG. 4 is a front elevational view of an inflatable frame for inflatable bed, the rear being identical.

The top and bottom form no part of the claimed design. The broken lines show environmental structure and form no part of the claimed design.
